Primary Examiner — Joseph Kukella*Assistant Examiner* — Lavon M. Amerson(74) *Attorney, Agent, or Firm* — Birchwood IP(57) **CLAIM**

The ornamental design for an electric bicycle, as shown and described.

DESCRIPTION

FIG. 1 is a front, right and top perspective view of an electric bicycle, showing our new design;

FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view of portion 9 encircled in FIG. 1;

FIG. 10 is an enlarged detail view of portion 10 encircled in FIG. 1;

FIG. 11 is an enlarged detail view of portion 11 encircled in FIG. 2; and,

FIG. 12 is an enlarged detail view of portion 12 encircled in FIG. 2.

The dot-dash broken lines depict the boundaries of the enlargements that form no part of the claimed design.
